UNITED STATES PATENT OFFICE.

THOMAS JEFFERSON MALCOLM, OF NATCHEZ, MISSISSIPPI.

PIANO-BRIDLE-STRAP FASTENER.

Application filed March 21, 1925. Serial No. 17,297.

This invention relates to a piano bridle strap fastener.

In upright piano actions the bridle strap connecting the hammer butt or check with the bridle wire is frequently broken and in certain types of piano actions it is an extremely tedious and difficult operation to replace the broken strap, owing to its inaccessibility and to the impractical type of fastener employed. It is, therefore, the object of the present invention to provide an extremely simple and practical fastener for the terminal of the bridle strap which is connected to a conveniently accessible part of the hammer check and further to provide, in a manner as herein-after set forth, a piano bridle strap fastener as an improvement upon the form of piano bridle strap fastener as disclosed in Letters Patent #1,343,516, granted to me June 15, 1920, and such improvement resides primarily in the manner of positioning the strap fastener element relative to the strap, whereby such element will coact with the wall of the opening in the hammer check to connect the strap to the check.

Further objects of the invention are to provide a piano bridle strap fastener, in a manner as herein-after set forth, which is simple in its construction and arrangement, strong, durable, thoroughly efficient in its use, and conveniently applied in operative position, and inexpensive to manufacture.

With the foregoing and other objects in view, the invention consists of the novel construction, combination and arrangement of parts, as herein-after more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a side elevation of a piano action, showing the adaptation therewith of a piano bridle strap fastener, in accordance with this invention.

Figure 2 is a fragmentary view, in front elevation, of a hammer check, showing the adaptation therewith of a strap fastener, in accordance with this invention.

Figure 3 is a perspective view of a piano bridle strap and fastener therefor, in accordance with this invention.

Figure 4 is a fragmentary view, in vertical section, illustrating the adaptation of a strap and its fastener with respect to a hammer check.

Referring to the drawings in detail, and particularly to Figure 1, there is illustrated a conventional type of piano action, the numeral 8 indicates the usual action rail pivotally supporting one of a series of butts 9 carrying the shaft 10 to which the hammer 11 is attached. The recessed projection 12, at the rear of the hammer butt, is engaged by the usual butt spring 13 and the hammer check 14 is attached to the butt 9 by the reduced shank 15 and is movable against the back check 16 during the return movement of the hammer 11. The bridle strap 17 is attached at one terminal to the check 14 and at its opposite end to the bridle wire 18 and in certain types of piano actions the strap is usually permanently attached by glue between the joints of the butt 9 and the shank 15 and is extended through an aperture 19 formed in the check 14.

The present invention provides an improved detachable fastener for the terminal of the bridle strap 17 and a comprehensive utilization of the opening 19 in the hammer check 14 for the reception of the detachable fastener for one terminal of the bridle strap 17.

Referring to Figures 1, 2, 3 and 4, where is shown one form of an improved piano bridle strap fastener, in accordance with this invention, the fastener consists of a compressible plug 20 formed from a single length of material and of tapered contour. The plug 20 is constructed of cork or similar material having the equivalent compressible and adhesive qualities of cork. Secured to the periphery of the plug 20 is the rear terminal portion 21 of the strap 17. Preferably the rear end edge of the strap 17 is flush with the edge at the reduced end of the plug 20. The end terminal portion 21 of the strap 17 is secured, in any suitable manner to the plug 20, preferably by a suitable adhesive, and said end terminal portion 20 when secured to the plug conforms to the curvature thereof.

When the strap 17 is connected up, the compressible plug is inserted through the opening 19 and said plug acts in connection with the wall of the opening 19 to detachably clamp the strap 17 to the check 14. The plug 20 is of a length to project rearwardly and forwardly of the check 14 when the plug is

mounted in the opening 19 and the wall of the latter is slightly tapered so a wedging action will be set up between said wall and the compressible plug 20.

- 5 In the form shown, the end terminal portion of the strap is secured to the outer face of the fastener and if the strap breaks the secured end can be disconnected from the fastener and the latter again used for a strap.
- 10 It is thought that the many advantages of a piano bridle strap fastener, in accordance with this invention, can be readily understood, and although the preferred embodiment of the invention is as illustrated and described, yet it is to be understood that changes in the details of construction can be had which will fall within the scope of the invention as claimed.

What I claim is:—

- 20 The combination with the hammer check of a piano action, said check formed with an opening having its wall tapered from end to

end, of a removable bridle strap having its rear terminal portion extending through and projecting from said opening, said strap having a part of its rear terminal portion seating directly upon the lower portion of the wall of said opening, and a tapered, one-piece, solid, compressible plug extending through and projecting forwardly and rearwardly of said opening, and having the lower part of its periphery secured to the upper face of said rear terminal portion, said rear terminal portion having its free end flush with the reduced end of said plug, and said plug wedging the rear terminal portion of said strap against the lower portion of the wall of said opening and further wedging against the remaining part of the wall of said opening whereby the strap will be secured to the check.

In testimony whereof, I affix my signature hereto.

THOMAS JEFFERSON MALCOLM.
